UNITED STATES PATENT OFFICE.

ALFRED M. ZIEGLER, OF BOSTON, MASSACHUSETTS.

CAST-OFF.

SPECIFICATION forming part of Letters Patent No. 748,908, dated January 5, 1904.

Application filed February 8, 1902. Serial No. 93,160. (No model.)

To all whom it may concern:

Be it known that I, ALFRED M. ZIEGLER, a citizen of the United States, residing at Boston, in the county of Suffolk and State of Massachusetts, have invented an Improvement in Cast-Offs, of which the following description, in connection with the accompanying drawings, is a specification, like letters on the drawings representing like parts.

This invention has for its object to improve wearing-apparel of whatever nature wherein ball-and-socket fastenings are commonly employed.

Prior to my invention it has been customary to suspend from the lower bar of a metallic loop applied loosely to a doubled portion of the shoulder-strap near its front end a cast-off comprising a leather or other strap provided with a post or stud and a suitable socket, both said post or stud and socket being permanently connected with the last-named strap. In this class of suspender it is customary to thread the material of the cast-off strap through the slot of the loop and to then permanently connect the cast-off strap with said loop.

In accordance with my invention I employ instead of the usual loop a loop-plate having permanently attached to it one member of a ball-and-socket fastening, the other member of said fastening being connected to a flexible member permanently secured to the button or end piece, so that when the suspenders are to be thrown off the shoulders it is only necessary to pull the flexible member of the ball-and-socket fastening that is attached only to the button or end piece from that member of said ball-and-socket fastening that is attached to the loop-plate secured to the shoulder-strap of the suspender. I have also devised a safety device that is connected with that member of the ball-and-socket fastening that is attached to the button-piece. This safety device coacts with the part of the ball-and-socket fastening attached to the loop-plate or with the loop-plate itself. This safety device sustains the wearing strain to which the ball-and-socket fastening of the suspender is subjected, and the cast-off having the socket embracing the post or stud is relieved from the duty of sustaining the strain on the suspender in use, the socket act-

ing to prevent the safety device from being disengaged from the ball member due to strains of use.

As I prefer to use two pieces of woven web for the button or end pieces at the front of the suspender, I have represented the safety device as a slotted sustaining-plate, and through the slots therein I pass the web constituting the button or end pieces, said web being free to slide in said slots and being stitched one to the other. That this plate may coöperate with the loop-plate and perform the functions of a safety device in one of the best forms now known to me I have provided said plate with a hole to engage the post or stud connected with said loop-plate. The safety device sustains the strain of the end pieces in wearing the suspenders. The socket coacting with the post or stud is carried by a piece of webbing that is permanently connected with the sustaining-plate. The safety device may, however, be a projection entering the loop-plate and extending into a slot therein.

The particular features in which my invention resides will be pointed out in the specification and set forth in the claims.

Figure 1 shows part of a suspender embodying my invention, one-half of the end piece being shown as partially finished at its end. Fig. 2 is an enlarged section in the line x. Fig. 3 is a view showing part of the cast-off shown in Fig. 1, but with the flexible member carrying the socket-piece turned down. Fig. 4 shows part of the suspender and one member of the cast-off. Fig. 5 shows in two views a modified member of the cast-off.

The shoulder-strap A is and may be of any usual shape and material.

The shoulder-strap A is threaded through the slot a in a metallic loop-plate a', having projecting from it a post or stud a², forming one member of a so-called "ball-and-socket" fastening, the post shown having a substantially spherical head and a shank. The upper edge of the lower cross-bar of the loop-plate a' is cut away through the slot a to leave a convex portion a³ immediately over the stud.

The cast-off is composed of a piece of flexible material b', provided with the second member or socket b of the ball-and-socket fastening, said socket being of the usual shape

and engaging the post or stud. This cast-off is attached by a rivet d to a sustaining-plate c' , having slots c and c^4 , that receive, respectively, the two narrow woven webs $f f'$, each 5 having a buttonhole e and which when united one to the other by stitches f^2 constitute the button or end pieces. These webs slide freely in these slots, and the cast-off having but one member of the ball-and-socket joint is connected with said plate permanently and is removable with it from the post or stud of the ball-and-socket fastening that is secured to the loop-plate always connected with the suspender-webbing. Herein I utilize the plate c' 15 as a safety device, and, as herein provided, I have shown two forms of safety device. One form is represented by the hole c^2 in an upward extension of the plate c' and the other by a projection or auxiliary holding device c^3 . 20 The hole c^2 may be slipped over the post or stud before the socket of the cast-off is applied thereto, and the plate in engagement with the stud helps sustain the strains of use on the button or end pieces, and the socket in 25 engagement with the post or stud acts to retain the plate c' in operative engagement with the loop-plate and its post or stud. So, also, the projection c^3 by entering the slot a and overlapping the convex portion a^3 thereof immediately above the base of the post or stud 30 serves to sustain a portion of the strain, thus relieving the strain on the post or stud. Either the plate with the hole embracing the stud or the projection overlapping the edge a^3 35 may be used as a safety device, and both together add to the greater efficiency of the safety device and not only serve to make the suspender more durable, but preferable for wear. In this way it will be noticed that the 40 cast-off may be entirely disconnected from the post or stud connected with the shoulder-strap when it is desired to throw the suspenders from the shoulders, leaving the post or stud connected with the shoulder-strap, 45 and so also it will be noticed that the strain on the cast-off is obviated.

It will be observed that the hole c^2 of the plate c' is slipped over the outer exposed end of the post or stud, and in this condition the 50 socket of the cast-off is applied to the post or stud and retains the safety device in position on the free outer end of the stud. To detach the end piece and cast-off from the shoulder-strap requires only that the cast-off be first 55 pulled off the stud, and thereafter the safety device may be disconnected from the post or stud or the plate.

My invention is applicable not only with 60 suspenders, but also with other classes of wearing-apparel, both for man and beast—as, for instance, gloves, shoes, skirt-bands, hose, blankets, and other things.

Having described my invention, what I claim, and desire to secure by Letters Patent, 65 is—

1. A slotted metallic loop-plate having a post or stud, a flexible cast-off having a

socket, and a safety device coacting with a rigid part of the loop-plate, to relieve the strain of the cast-off and socket on the post 70 or stud.

2. A fastening for detachably connecting two parts, one of said parts being provided with a post or stud, and the other part with a socket to engage said post or stud, combined with a safety device secured to the part carrying the socket and adapted to engage the post or stud of the fastening between the socket and the part carrying the post or stud. 80

3. A loop-plate having a post or stud, a flexible strap having a socket for engagement with the post or stud, means with which said flexible strap is connected, and a safety device also connected to the means carrying 85 the flexible strap and engaging the post or stud behind the part thereof engaged by the socket.

4. A plate provided with a post or stud, a part to be sustained by said plate, a cast-off 90 secured to said part and having a socket to engage said post or stud, and a safety device also secured to said part and detachably connected to the said plate, the socket of the cast-off engaging the post or stud outside of 95 the safety device to prevent disengagement of the safety device from said plate.

5. A plate having a post or stud, a sustaining-plate detachably hung on said post or stud and a piece of flexible material connected with said sustaining-plate below the 100 point of attachment of the sustaining-plate with the stud or post, said piece of flexible material being provided with a socket to engage said post or stud and maintain said sustaining-plate thereon. 105

6. A slotted plate having a post, a sustaining-plate having a hole engaging said post, flexible material connected with said sustaining-plate below the hole therein engaging 110 said post, and provided with a socket embracing the outer end of said post.

7. A plate having a post provided with a ball-shaped head, a socket, means carrying said socket, a sustaining-plate hung on said 115 post, and a suspender-end piece carried by said sustaining-plate, said socket engaging the ball-shaped head outside the sustaining-plate and retaining the plate on said post.

8. A slotted plate having a post, a sustaining-plate embracing said post and provided with a projection entering said slot, and means carried by said sustaining-plate and engaging the outer end of said post after the sustaining-plate has been applied thereto to 125 retain the sustaining-plate on the post.

9. A slotted plate having a post, a second plate having a flexible strap suitably connected at one end to said second plate, and also provided with means for detachably securing the second plate to the slotted plate, said flexible connection having a socket at its free end to engage the said post and retain the plates in engagement. 130

10. A plate adapted to be sustained by a strap, said plate having one member of a ball-and-socket fastening, and a slotted plate adapted to sustain two flexible end pieces, 5 combined with a flexible strap provided at its free end with the other member of the ball-and-socket fastening, said slotted plate having an auxiliary holding device to engage the first-named plate.
- 10 11. In a suspender, a plate having a post or stud, a metallic safety device comprising a projection to engage the said plate, a flexi-

ble piece secured to the metallic safety device and provided with a socket to engage said post or stud to maintain the projection 15 of the safety device in engagement with the plate.

In testimony whereof I have signed my name to this specification in the presence of two subscribing witnesses.

ALFRED M. ZIEGLER.
